(Continued)

FIG. 26 is a rear perspective view thereof; and, FIG. 27 is a perspective view thereof in open position. The dash-dash broken lines in the drawings are for the purpose of illustrating portions of the scanner that form no part of the claimed design. The scanner is shown with a symbolic break in its height in the first embodiment, represented by break lines shown in dot-dash broken lines. The dot-dot-dash broken lines in the drawings are for the purpose of showing a boundary between portions of the scanner that form claimed subject matter and portions of the scanner that form no part of the claimed design. The break lines and any portion of the article between the break lines form no part of the claimed design.
